H. C. Dart,
Beer Cooler.

No. 92,429.

Patented July 13, 1869.

United States Patent Office.

HENRY C. DART, OF NEW YORK, N. Y.

Letters Patent No. 92,429, dated July 13, 1869.

IMPROVED BEER-COOLER.

The Schedule referred to in these Letters Patent and making part of the same.

To all whom it may concern:

Be it known that I, HENRY C. DART, of the city and State of New York, have invented and made a new and useful Improvement in Coolers for Beer, &c.; and I do hereby declare the following to be a full, clear, and exact description of the said invention, reference being had to the annexed drawing, making part of this specification, wherein

Figure 1 is a side view of the cooler;

Figure 2 is a plan of the same;

Figure 3 is a vertical section of the apparatus transversely, at the line $z z$; and

Figure 4 is a detached plan and side view of the hooks that are used for uniting the sheet-metal forming the chambers.

Similar marks of reference denote the same parts.

This invention consists in a series of corrugated metallic chambers, in combination with supply and delivery-pipes, arranged so that the cooling-water enters at one end of one chamber and at the opposite end of the next chamber, and passes away by separate delivery-pipes; thereby the cooling-action is equalized.

Furthermore, I construct the sheet-metal chambers with interior hooks and eyes, to sustain the parts against either the pressure of the water or any external atmospheric pressure, thereby preventing the sheets moving by the pressure, or buckling or changing shape under expansion or contraction of the metal.

In the drawing, I have represented the cooler as formed of four corrugated sheet-metal chambers, $a b c d$.

The horizontal edges of the corrugated sheets of one section lap upon the edges of the section next below, so as to form surfaces over which the beer runs, and is received at the bottom in a trough.

Previous to the sheets being soldered together, I attach, by solder or brazing, on opposite sides of the respective corrugations, and at suitable distances apart, the eyes e and hooks i , as seen in fig. 4.

These are all simultaneously hooked together in each section, by an end-movement of the sheets after one corrugated sheet is placed on the other, and to keep the corrugated sheets apart, I introduce strips or bars, o , at suitable distances apart, running transversely of said corrugations. These hooks, eyes, and bars firmly connect the corrugated sheets together, and keep the parts at the proper distance from one another.

The horizontal edges of the sheets are then soldered together, to form the chambers, and the end plates f and g are attached and close the ends of the chambers. These plates are to be soldered to place, and may be made in sections, for the respective chambers $a b c d$, or they may extend from top to bottom, as shown.

The beer is introduced through a pipe, h , into the

trough k , and runs from the edge of the trough over the surfaces of the chambers, there being a pipe, k' , in the trough, with a longitudinal slit, to facilitate the equal distribution of the beer.

l is the inlet cold-water pipe, with a cock, 1, to the section or chamber a .

l' is a horizontal branch to the vertical pipe l' , having cocks, 2 and 4, to supply cold water to the sections b and d , and 3 is a cock to supply water to the chamber c .

By means of these cocks the proper amount of water can be supplied to the respective chambers. For instance, if it is desired to suddenly check the temperature of the beer, more water can be supplied to the chamber a , and if the cooling is to be mostly effected at the latter part of the operation, a larger supply must be given to the chamber d , or the supply may be nearly uniform, and the temperature reduced gradually.

The water flows into alternate opposite ends of the respective chambers, and is taken away from the opposite end of each chamber to that at which it entered, by the respective pipes 11, 12, 13, and 14, leading into the overflow-pipe n or n' , connected together by the pipe n^1 .

These branch-pipes, 11, 12, 13, 14, pass away from the lower portions of the respective chambers, and, in order to allow of the escape of air, the small pipes 5, 6, 7, 8, are introduced, opening either into n or n' .

The overflow from n is to be as high as the top of the chamber a , so as to keep the chambers full.

By this construction, the temperature of any part of the apparatus can be regulated at will, and the cooling of the beer is equalized, in consequence of the water being admitted from alternate opposite ends of the chambers.

What I claim, and desire to secure by Letters Patent, is—

1. The series of horizontal corrugated chambers, placed one above the other, in combination with the inlet-pipes and cocks, and outlet pipes, arranged in the manner and for the purposes set forth.

2. The hooks i and eyes e , united to the interior surfaces of the corrugated metallic sheets, and set together, as and for the purposes set forth.

3. The trough k , fitted with the horizontal pipe within it, having a longitudinal incision, to equalize the flow of the beer, which runs over the edge of the trough, substantially as specified.

In witness whereof, I have hereunto set my signature, this 10th day of June, A. D. 1869.

HENRY C. DART.
